UNITED STATES PATENT OFFICE

ROSCOE D. POOLE, OF DANVERS, MASSACHUSETTS, ASSIGNOR OF ONE-HALF TO HERBERT A. MILLER, OF DANVERS, MASSACHUSETTS

LAST

Application filed February 5, 1930. Serial No. 426,120.

My invention relates to boot and shoe lasts and it has for its object to provide an improved device of the class described.

In the manufacture of certain kinds of boots and shoes, particularly stitch-down and turned shoes, it is the practice to place both the sole and the upper upon a last to which they are held while the upper is sewed to the sole.

10 The usual practice has been to secure the sole to the last by means of two tacks, one driven through the sole into the bottom of the last at the fore part of the latter and the other driven into the bottom of the last adjacent 55 to the heel thereof. These two tacks were depended upon to hold the sole in proper position with relation to the last while the upper was being sewed, or otherwise fastened, to the sole.

20 This old method was objectionable for the reason that the sole was mutilated and disfigured by the tacks and the repeated or continued driving of tacks into the bottom of the last soon destroyed the latter or rendered 60 it unfit for use. Furthermore the shoemaker would often drive a tack through the sole and into the last and then, if the sole was not in correct position with relation to the last, it was necessary for him to remove 65

30 one or both of the tacks and after readjusting the sole again fasten it to the last by means of two tacks.

Owing to the fact that these tacks were usually driven fully into the sole so that 70 the heads thereof were flush with the tread side of the latter, the removal of a tack could not be effected by means of a tack-pulling instrument without further mutilation and disfigurement of the tread side of the sole.

40 Heretofore it has been proposed to construct a two-part last with two or more spike members movably mounted in sockets or chambers at the bottom of the last and operated by relative movement of the two parts 75 of the last so that when said two parts were adjusted relatively for use the barbs of the spike members were projected from the bottom of the last into the sole, and when adjusted relatively for removal of the last from 80 the shoe said barbs would be retracted.

Lasts constructed in this fashion did not fully meet the requirements for the reason that the spike members served only to hold the sole against edgewise displacement relatively to the last. So far as I am aware 55 has been no last construction heretofore proposed which would function to positively fasten the sole to the bottom of the last so as to hold it against bodily movement directly away from the latter.

80 My invention provides a last for use in making boots and shoes provided at its bottom with means for positively engaging and locking a sole in position against the bottom thereof so that said sole cannot move either 60 edgewise with relation to, or bodily away from, the last.

65 In the best form of my invention the sole-engaging means of the last does not project beyond the tread of the sole and it operates to hold the latter in position against the bottom of the last by engagement with the top portion only of the sole so that the bottom of the latter is not disfigured or mutilated.

70 Thus by my invention the use of tacks is 75 obviated as are also the objectionable features above pointed out as characterizing the constructions heretofore proposed.

In the accompanying drawings: 80 Figure 1 is a longitudinal sectional view of a boot and shoe last constructed in accordance with my invention showing a sole attached thereto and indicating, by dotted lines, the upper of a shoe.

85 Figure 2 is a plan view of the last shown in Figure 1.

Figure 3 is an elevation of the fore-part spike member hereinafter described.

90 Figure 4 is an elevation, partly in section, of the bushing provided for the spike member of Fig. 3.

Figure 5 illustrates an alternative construction.

95 The body 1 of the last herein illustrated is preferably made from one piece of material, preferably wood, and may be provided, as usual, with a socket 2 to receive the spindle of a jack.

Near its rear end the body 1 is formed with 100 a vertical bore into which is forcibly driven,

or otherwise fixed, a tubular bushing 3 whose interior provides a chamber 8 for a sole-engaging screw-member 4 provided with a slotted head 5 which may be reached and operated by means of a screw driver inserted in the upper open end of the bushing 3.

At its lower end the screw-member 4 is more or less pointed and formed with a screw thread 6 so that, by means of the screw driver referred to, the member 4 can be forced downwardly against a sole 7 placed beneath the last body 1, and then rotated thereby to screw the lower end of the latter into the material of the sole 7 from the top side thereof.

The chamber 8 provided by the bushing 3 is formed with an annular shoulder 9 which serves as a stop against which the lower end of the head 5 of screw-member 4 is brought to bear to limit the downward movement of the latter. This shoulder 9 is positioned so that the lower threaded end 6 of screw-member 4 cannot be projected below the bottom of the last more than the thickness of the sole 7.

As means for yieldingly holding the screw-member 4 retracted and sheathed within its bushing 3 when not in use I provide a coiled spring 10 bearing at its lower end against an annular shoulder 11 provided within the bushing 3, and at its upper end against the head 5. When screw-member 4 is rotated in a direction to disengage it from the sole 7 the spring 10 moves said screw-member inwardly and upwardly until its head 5 comes to bear against an annular shoulder 12 provided within the bushing 3 near the upper end thereof. This shoulder 12 is the lower end of a sleeve or ferrule 13 fixed in position within the upper end of bushing 3.

It will be clear that when the screw member 4 is in threaded engagement with the material of the sole 7 the heel portion of the latter is not only held against edgewise displacement in any direction with relation to the last, but it is also fastened to the last so that it is held against bodily movement away from the same.

The fore-part of my improved last is made with an obliquely disposed bore into which is forced, or otherwise fixed, a tubular bushing 14 providing a chamber 15 within which is movably mounted a spike member 16 having its lower end portion made as a smooth needle point 17 and its upper end with a slotted head 18.

Near its lower end the bushing 14 is made with an annular shoulder 19 providing an abutment-seat for one end of a coiled spring 20 surrounding the shank of spike-member 16 and bearing at its upper end against the head 18.

As shown in Fig. 3 the lower end portion of the head 18 is made upon its exterior with two or three screw thread convolutions 21 to co-operate with two or three screw thread convolutions 22 provided within bushing 14,

said threads 22 being shown clearly in Fig. 4.

Adjacent the upper end of the bushing 14 the latter is also provided upon its interior with an annular shoulder 23 which is the inner end of a short sleeve or ferrule 24 fixed in position within said bushing. Thus the upper end of the bushing 14 is open to admit a screw driver by means of which the spike-member 16 may be operated.

In Fig. 1 of the drawings the threads 21 of spike-member 16 are shown as in engagement with the threads 22 of bushing 14, and the inner end of the head 18 is shown as bearing against an annular stop-shoulder 25 provided within said bushing. With the spike-member 16 in this position its lower pointed end 17 is projected beyond the bottom of the last into the sole 7 and it will be clear that, because of the oblique disposition of the axis of bushing 14 with respect to the axis of the bushing 3, the sole cannot slide downwardly off from the pointed end 17 for the reason that to do so said sole must move forward with relation to the last which it cannot do because it is held against edgewise movement in that direction by the lower end of the screw-member 4.

Thus, when screw-member 4 and spike-member 16 are both in engagement with the sole of the shoe that is being made, said sole cannot be displaced in any direction relatively to the last, and furthermore, since in the best form of my invention neither the screw-member 4 nor the spike-member 16 perforates the sole, the outer tread side of the latter will not be marked or disfigured in any way. Thus my invention provides means for positively engaging the top side portion only of the sole to fasten the latter to the last and hold it against displacement in any direction.

To disengage the spike member 16 from the sole 7, said spike-member is rotated in a direction to unscrew the threads 21 from the threads 22 and as soon as these threads are disengaged the spring 20 shoves the spike-member upwardly into position against the stop shoulder 23, thereby sheathing the lower end of said spike member wholly within the bushing 14.

It will therefore be clear that when the last is not in use the pointed ends of the members 4 and 16 are wholly inclosed and therefore cannot engage or injure other things with which the last may come into contact.

It will also be clear that I have provided very simple and efficient means for fastening the sole to the last against displacement relatively thereto while it is being sewed or otherwise fastened to the upper of the shoe, the latter being indicated by dotted lines at 25, Fig. 1.

In Figure 5 I have illustrated an alternative construction wherein the spike member 16

is extended upwardly beyond the top of the last and provided with a finger piece or head 16a by means of which it is manipulated. Also, the screw member 4 at the heel of the 5 last is extended upwardly beyond the top of the latter and provided with a finger piece 4a by means of which it is manipulated. In this form of the invention the use of a screw driver is dispensed with.

10 It will be noted that the shoulder 9 is positioned so as to stop the downward movement of the screw member 4 before the lower pointed end thereof passes through the sole S. Likewise the shoulder 25 arrests the 15 downward movement of the spike member 16 before the lower end thereof is forced entirely through the sole.

It will therefore be clear that the tread 20 side of the sole S is not in any way mutilated or marked by the means through which it is secured to the last during the operation of making the shoe.

What I claim is:

25 1. A last having its forepart made with an obliquely disposed chamber extending from the top of the last forwardly to the bottom thereof and its heel-part made with a vertically disposed chamber extending from the top of the last to the bottom thereof; 30 a sole-engaging spike-member adjustably mounted within said obliquely disposed chamber, and a sole-engaging screw-member adjustably mounted within said vertically disposed chamber, said two members being 35 operable to engage and disengage a sole and when in engagement with the latter serving to hold said sole against displacement in any direction relatively to the last.

40 2. A last constructed in accordance with claim 1 wherein each member is rotatably mounted within its chamber and wherein means is provided for moving said spike-member longitudinally in its chamber toward and from the sole when said member is 45 rotated and for holding said spike-member in its sole-engaging position.

50 3. A last constructed in accordance with claim 1 wherein each member is rotatable and also endwise movable in its chamber and including also means rendered effective by rotary motion of said spike-member in one direction to hold the same in its sole-engaging position, and spring means for yieldingingly holding both of said members retracted 55 and sheathed within their respective chambers when said screw-member is not in engagement with a sole and said holding means is rendered ineffective by rotary motion of said spike-member in the opposite direction.

60 Signed by me at Danvers, Essex County, Massachusetts, this 4th day of February, 1930.

ROSCOE D. POOLE.
